UNITED STATES PATENT OFFICE.

EDGAR M. SMITH, OF NEW YORK, N. Y., ASSIGNOR TO OTTO R. BARNETT, OF CHICAGO,
ILLINOIS.

ANTICREEPER.

1,078,562.

Specification of Letters Patent. Patented Nov. 11, 1913.

Application filed January 20, 1913. Serial No. 743,094.

To all whom it may concern:

Be it known that I, EDGAR M. SMITH, a citizen of the United States, residing at New York city, in the county of New York and State of New York, have invented certain new and useful Improvements in Anti-creepers, of which the following is a specification.

My invention relates to devices for checking the tendency of railroad rails to creep longitudinally in the direction of travel over the track, such devices being commonly called anti-creepers, rail stays or rail anchors.

One of the objects of the invention is to provide a device of this sort which will not cause the tie against which it abuts to cant or turn in the road bed. Most of the rail anchors now in use are objectionable to a greater or less extent because they operate in this manner. If the tie is thus canted or turned it is necessarily loosened in the ballast and if a tie plate is used the turning of the tie brings the sharp edge of the tie plate against the bottom of the rail. Both these results are objectionable for reasons well understood by railroad men.

A further object is to provide a simple and effective device which will serve the double purpose of tie plate and anti-creepers.

A further object is to provide a device of this character which can be very cheaply manufactured, for example, from rolled stock.

A further object is to provide an anti-creepers which is bolted to the rail, so that its hold thereon is positive, but which is also constructed so that it has a frictional grip on the base of the rail that relieves the bolt of some of the stress to which it would be otherwise subjected. By this means the shearing of the bolt or the loosening of its connection with the rail and anti-creepers is minimized.

The invention is illustrated, in a preferred embodiment, in the accompanying drawing, wherein—

Figure 1 is a plan view of the device shown as applied to a railroad rail; Fig. 2, a side elevation; Fig. 3, a sectional view taken on line 3-3 of Fig. 1, and Fig. 4, a perspective view of the device.

Like characters of reference designate like parts in the several figures of the drawing.

Referring to the drawing, A designates a

railroad rail of T section, and B one of the cross ties on which the rail is supported.

The anti-creeping device of my invention is preferably made of a single piece or sheet of rolled metal bent so as to provide a flat plate C which intervenes between the base D of the rail and the cross tie B, and so as to provide an upstanding web E which is designed to lie close to the upstanding web F of the rail; the intervening metal G of the anti-creepers having approximately the slant of the upper surface of the base flange so that a jaw is provided into which one of the base flanges fits. The web E is formed with a perforation H and the web F of the rail is similarly perforated, the rail being positively attached to the anti-creepers by a bolt I passing through these perforations. The metal of the anti-creepers will preferably have some elasticity so that by making the jaw a trifle narrower than the base flange of the rail the drawing up of the nut J on bolt I will produce a frictional grip of the anti-creepers on the rail. A portion of the forward edge of the plate C is bent down so as to provide a flange K which is designed to abut against the face of the tie B.

The device is preferably spiked to the tie by ordinary railroad spikes and to this end is provided with the spike holes L in the jaw portion of the device and the spike hole M in the opposite edge of the plate C.

In order to further increase the frictional grip of the device on the rail the edge of the plate C opposite the jaw is formed with slits N and portions of the edge of the plate, designated O and P, are bent up a trifle. This bending is preferably done after the anti-creepers is put in place on the rail, with the result that the rail is further crowded into the jaw, although if desired the lugs may be bent up when the device is manufactured.

Q designates the spikes used for securing the device and the rail to the cross tie.

It will be observed that the device can be made of a single rectangular piece of rolled stock. This piece of metal has simply to be punched, slit and bent into the desired configuration. Therefore the device can be very cheaply manufactured. It serves the function both of a tie plate and anti-creepers. Its hold on the rail is positive. At the same time there is no danger that undue stress will loosen the bolt connection or shear off the

bolt inasmuch as the frictional grip of the device on the rail relieves the bolt of some of the stress to which it otherwise would be subjected. As the device engages the two faces 5 of the tie—the front vertical side and the top surface—and is, furthermore, spiked down to the tie, there is no danger that the gripping action will cant the tie. But even if such canting should take place the tie plate 10 portion of the device will not be turned as is the case with separate tie plates used in connection with the types of anti-creepers now in common use. The lugs O and P, when bent into their oblique position, tend 15 to increase the frictional grip of the device on the rail. The tendency of the rail to creep forward takes place, of course, while the train is passing over the rail in question. The passage of the train necessarily develops 20 some vibration and lateral stresses and when these are absorbed, as they are to a certain extent by the lugs O and P, the tendency to longitudinal creep is checked. The spiking of the device to the tie and its frictional 25 grip on the rail check any tendency there may be to creeping in the opposite direction, that is, in the direction away from the tie in question.

I claim:

- 30 1. A device of the character described comprising a plate intervening between the base of the rail and one of the cross ties on which the rail is supported, a web adapted to be bolted to the upstanding web of the 35 rail, means providing a jaw adapted to take a frictional grip on one of the base flanges of the rail, and a lug or lugs at the edge of the plate opposite from said web which are bent up to a position oblique to the rest of 40 the plate, for the purpose specified.
2. A device of the character described comprising a plate intervening between the base of the rail and one of the cross ties on which the rail is supported, a web adapted 45 to be bolted to the upstanding web of the rail, means providing a jaw adapted to take a frictional grip on one of the base flanges of the rail, and a lug or lugs at the edge of the plate opposite from said web which are bent up to a position oblique to the rest of 50 the plate, said device being formed with spike holes whereby it may be spiked to the track.
3. A device of the character described

comprising a plate intervening between the 55 base of the rail and one of the cross ties on which the rail is supported, a web adapted to be bolted to the upstanding web of the rail, means providing a jaw adapted to take a frictional grip on one of the base flanges 60 of the rail, a lug or lugs at the edge of the plate opposite from said web which are bent up to a position oblique to the rest of the plate, and a depending flange in position to abut against the tie. 65

4. A device of the character described comprising a plate intervening between the base of the rail and one of the cross ties on which the rail is supported, a web adapted to be bolted to the upstanding web of the 70 rail, means providing a jaw adapted to take a frictional grip on one of the base flanges of the rail, a lug or lugs at the edge of the plate opposite from said web which are bent up to a position oblique to the rest of the 75 plate, and a depending flange in position to abut against the tie, said device being formed with spike holes whereby it may be spiked to the tie.

5. A device of the character described 80 consisting of a single sheet of metal bent so as to form a jaw for one edge of the base of a rail, a plate extending under the base of the rail and projecting beyond the other edge thereof, and an upstanding web adapted 85 to be bolted to the vertical web of the rail, one of the transverse edges of the device being formed with slits and the metal between the slits bent down so as to provide a depending tie-abutting flange. 90

6. A device of the character described 95 consisting of a single sheet of metal bent so as to form a jaw for one edge of the base of a rail, a plate extending under the base of the rail and projecting beyond the other edge thereof, and an upstanding web adapted 100 to be bolted to the vertical web of the rail, one of the transverse edges of the device being formed with slits and the metal between the slits bent down so as to provide a depending tie-abutting flange, the edge of the plate opposite the jaw being formed with slits so as to provide bendable lugs.
